[57] CLAIM

The ornamental design for a hook, substantially as shown and described.

DESCRIPTION

FIG. 1 is a front elevation view showing my design;
FIG. 2 is a rear elevation view thereof;
FIG. 3 is a left side elevation view thereof, the right side elevation view being a mirror image of said left side view;
FIG. 4 is a top plan view thereof;
FIG. 5 is a bottom plan view thereof; and
FIG. 6 is a sectional view thereof taken in the direction indicated by the cutting plane 6—6 in FIG. 3, and drawn to a somewhat larger scale.
